SAMUEL SAUNDERS, OF MANCHESTER, ENGLAND.

AUTOMATIC CONTROLLING MEANS FOR HEATING AND LIGHTING INSTALLATIONS AND SUCH LIKE.

1,272,121.

Specification of Letters Patent.

Patented July 9, 1918.

Application filed October 10, 1917. Serial No. 195,669.

To all whom it may concern:

Be it known that I, SAMUEL SAUNDERS, subject of the King of Great Britain and Ireland, residing at 43 Lower Morley street, 5 Manchester, in the county of Lancaster, England, heating and ventilating engineer, have invented new and useful Improvements in Automatic Controlling Means for Heating and Lighting Installations and Such 10 like, of which the following is a specification.

This present invention relates to improvements in automatic controlling means for heating and lighting installations and such 15 like.

It is known to employ alarm clocks capable of being set, whereby when the alarm spindle moves, mechanism is released or actuated which (through weights or otherwise) operates dampers, or switches, or valves, etc., for the automatic performance of some particular office, and it is to this 20 class of device that my invention relates.

I make use of a carrying board or any appropriate fixture and on this I mount means for supporting or incasing an alarm clock. The clock may be removable from supports, or it may be carried on a hinged or movable part of the casing which is designed to 25 30 expose the face of the clock at the front. Such a clock can be readily fixed in the hinged part of the casing and so is easily swung out on the casing hinges for winding-up, setting and other purposes. I use an eight 35 day or other long period clock with an alarm mechanism capable of being set at any time in the twenty-four hour period as is known, and I may arrange to silence the alarm sounding appliances if such are fitted 40 on the clock. On certain alarm clocks, a press-down or other device is fitted, which, when acted on, stops the alarm.

I propose to use such an arrangement of mechanism as will only call for a winding 45 of the clock and the alarm spindle say once a week; and so attention to the release or actuating mechanism once a day is alone necessary and the alarm needs no daily winding. I also use such a combination as will 50 prevent the alarm wind spindle from running down completely should the release or actuating mechanism be not re-set on any particular day.

To carry out my object I preferably arrange 55 to act on the mechanism which stops

the alarm wind spindle, immediately the same has performed its function and effected release. The way of doing this would vary according to the form of stop alarm appliance. In that class of clock where a 60 push down spindle exists, a pivoted lever would form a simple actuating means.

The use of time recording mechanism for performing a service automatically at intervals over a period of days has been hampered by inability to skip or miss a day or a number of days and yet to be able to bring the mechanism into action after skipping or missing a period. As an example, when dealing with automatic heating or light or 65 other controlling means, it is obvious that in the majority of cases it is desirable to be able to suspend action on Sundays without interfering with due performance of the desired office on the Monday. I so arrange 70 that a day or days may be cut out or omitted by the mechanism.

In the simplest way of effecting this part of my object I arrange to make the "release lever" inoperative, when desired, but 75 by means which make such release lever again automatically operative after being out of action for a period of 24 hours or other desired length of time.

My invention is illustrated in the attached 80 drawings, wherein:—

Figure 1 shows a front view of clock controlled mechanism embodying the features of my invention.

Fig. 2 is a sectional view. 90

Fig. 3 is a face view and shows the clock turned away from the support through an arc of 180°, to more fully expose the mechanism.

Figs. 4 and 5 are detail views of the lever 95 mechanism which acts on the alarm push-down spindle to at once stop the alarm wind mechanism as soon as the desired office has been performed.

Fig. 6 is a detail view of the release lever 100 pivot or fulcrum.

Figs. 7 and 8 are enlarged detail views of the combined means which permit of the cutting out of a day or days.

In describing my invention in detail I will 105 deal with mechanism suitable for an alarm clock with the known push-down spindle. Such an alarm clock is shown in the drawings and is marked *a*. It is removably mounted on the movable part of a casing *a'*, 110

a^2 , the part a' being fixed to the supporting board A, and the part a^2 carrying the clock being hinged at a^3 .

I fit the alarm wind spindle b with a small plate b' or the like having two projecting pins b^2, b^2 which device also serves for winding the said spindle b . I use a release lever c, c' , conveniently centered on a cast-metal plate c^2 , and the upper part c of this lever lies contained in the wooden casing which incloses the clock, the lever lying behind or in rear of the clock when the casing is closed and being guided by the slotted bracket j . The lever is acted upon by a small plunger d backed-up by a spring; or it might be held up by a weight or the like. Such lever has a projection c^x which is acted upon by the pins b^2, b^2 , on the small plate b' on the alarm wind spindle b when the alarm goes off, and also another projection c^y which operates the lever e to act on the push down spindle.

This lever e is suitably shaped and carried on a projecting post or spindle e' and has an arm e^2 to act on the push down spindle f of the alarm clock and a longer arm e^3 which normally rests on a stop e^4 . Upon such longer arm is a triangular plate g pivoted at g' , the vertical edge of said plate normally resting against a pin g^2 on the long lever arm. The result of this construction is, that when the alarm wind spindle b rotates, one of its pins b^2, b^2 acts on the part c^y of the release lever c and moves it angularly and say to the right as will be understood. In moving to the right, the projection c^y on the upper end of the release lever pushes past and displaces the pivoted triangular plate g without influencing the pivoted lever e . When the pin b^2 has moved the release lever c so as to free the release or disengaging or actuating mechanism, the pin b^2 escapes clear of said lever, whereupon the spring pressed plunger d at once pushes back the release lever c ready for re-setting. In pushing back the release lever c , the upper projection c^y encounters the pivoted triangular piece g and so the pivoted lever e is at once actuated to operate the push down spindle f and so to stop the alarm wind spindle. I find that about half a revolution of the alarm wind spindle is enough movement for the object in view, so that the pin plate automatically comes into proper position every time, but this may vary considerably.

I may use a rotatory grooved pulley h (or other gear device) with hand lever h' , in combination with the release lever, said pulley device being centered on a stud h^2 on the cast plate c^2 . The grooved pulley has a pin h^3 which engages a notch or cut-away portion c^5 in the release lever half c' , whereby the weights i supported on the chain i' , and which weights do the work, are held sus-

pended. The grooved pulley h has attached to it flexible connections such as a chain k or chains or other motion communicating devices to operate the dampers, doors, switches, valves, or such like, which require control, whereby when the pulley h is released, the weights i turn same and effect a pulling on the chain k or the like.

If the release lever c, c' were made in one piece or a single entity actuation of the control mechanism would take place at every movement of the alarm wind spindle, but, for the reasons indicated (that is the power to cut out a day or days at will) I prefer to make the release lever in two parts c, c' the upper part c being hinged or jointed to or working on the same pivot c^y as the lower, the complete lever having a fulcrum say coinciding with the hinge or joint at the point c^y . The upper half of the release lever is, as already stated, acted on by the plunger d backed up by a spring or otherwise returned to its required position. From the lower half of the release lever, extends an arm or support c^6 , which is bored and carries a quadrant or notched disk m shown as cut with eight teeth to provide for service over a period of 7 days. The quadrant or notched disk is movable around a center pin m' and has a stop-piece m^2 , which, when in the position seen in Fig. 7, abuts against the arm c^6 . To the part c of the release lever, is attached a pawl or catch n fulcrumed at n' the hooked extremity of which engages one of the teeth of the quadrant or notched disk m . According to the marked number of the tooth on the quadrant or notched disk m engaged by the pawl or catch n that period of days will be omitted. For example should it be desired to suspend actuation of the controlled mechanism for three days, the pawl n is lifted and the toothed quadrant or notched disk m turned forward three teeth. The effect of this is, that when the alarm next goes off, the quadrant or notched disk alone is moved or advanced a tooth and the same on the second and third days, but on the third day the position is such that the pin or stop m^2 has reached the arms c^6 and so on the fourth day the release lever as a whole is actuated and the desired office performed automatically at the predetermined time.

Obviously the cutting out form of connection used with the release lever may be varied, but I have illustrated the simplest arrangement known to me.

By my invention I can do all that is necessary with a weekly winding of the clock and the alarm spindle, and I actuate the stop alarm spindle mechanism immediately the automatic office is performed. It is also obvious I arrange for the actuation of the stop alarm mechanism in the same manner (even if the release lever or the like, due to care-

lessness, be not re-set) because the release lever receives movement from the alarm spindle even in that event.

It must be understood that I do not limit myself to any form of release lever or form of setting mechanism to be released; the measuring out of movement of the alarm wind spindle and the immediate automatic actuation or disengagement of the stop alarm mechanism with the prevention of running down of the wind alarm spindle in case of non-resetting, and the power to cut out a day or days being the important features.

15 I wish it to be understood that mechanism embodying the features described, would require to be of somewhat varied form according to the purpose in view.

The invention is particularly useful for 20 the automatic openings of draft doors, dampers, and the like of heating plant at a predetermined time in the early morning before the arrival of the workers whereby a working temperature is assured without requiring manual attention before opening time.

25 I declare that what I claim is.

1. An automatic control mechanism comprising a movable alarm clock, a stop alarm press fitting thereon, a rotary mounting on 30 the back of said clock, a compound release lever device, a fulcrum for such lever device, a ratchet in connection with one part of the lever, a connecting device with another part of the compound lever whereby 35 the lever elements are inter-connected, a rotatable pulley worked by a load on release of the compound lever and trip lever mechanism comprising a pivoted lever and hinged part operated on the backward movement of 40 the compound lever said pivoted lever working the stop alarm press fitting.

2. An automatic control mechanism comprising a movable alarm clock, a stop alarm fitting on said clock, a rotary alarm wind 45 mounting on said clock, a release lever device formed in two parts, a toothed device on the one part and a connection to said toothed device on the other part, a release pulley, a load to work such pulley on release, and 50 a stop on said pulley, and a trip lever with pivoted part and pins, the trip lever mechanism being operated on the backward movement of part of the release lever and serving to actuate the stop alarm fitting on 55 the clock.

3. An automatic control mechanism con-

sisting of a movable alarm clock, a stop alarm fitting on the clock, a rotary alarm wind mounting on the alarm wind spindle, a compound release lever consisting of an upper and a lower part, a fulcrum for the compound release lever, a quadrant fitting on the one part, a pivoted inter-connecting device on the other part, means to hold the compound lever, a movable connection operating device capable of being set, a stop thereon, and a trip lever mechanism mounted above the clock and a hinged plate on said lever whereby the trip lever works the stop alarm fitting on the clock on the return 70 movement of the upper part of the compound release lever.

4. An automatic control mechanism comprising a support, a movable alarm clock, a stop alarm fitting and a rotary alarm spindle 75 mounting on said clock, a compound release lever, a fulcrum therefor, a ratchet disk on one part of the compound release lever and a connecting device to the ratchet disk mounted on the other part of lever, 80 means to keep the upper part of the compound release lever up to its work, a rotary device with operating connections therefrom and a stop for the lower part of the compound release lever, and trip lever mechanism consisting of a pivoted lever, a hinged plate and pins whereby the upper part of the compound release lever operates the stop alarm mechanism on backward movement 85 all as set forth.

5. An automatic control mechanism comprising a support, a movable alarm clock, a hinged carrier for said clock, a stop alarm fitting and an alarm spindle mounting on 90 said clock, a compound release lever consisting of an upper and lower part, a ratchet disk on the lower part, a link connection to said disk on the upper part, a rotary operating pulley and connections and a stop for the lower part of the release lever, and 95 enclosed trip lever mechanism consisting of a pivoted lever, hinged parts and stop pins operated by the upper part of the release lever to act on the stop alarm fitting on the clock all in combination and as set forth.

100 In testimony whereof I have signed my name to this specification in the presence of two subscribing witnesses.
